UNITED STATES PATENT OFFICE

2,585,265

FAN BLADE STRUCTURE

George L. Moeller, St. Louis, Mo., assignor, by
mesne assignments, to Knapp-Monarch Co.,
St. Louis, Mo., a corporation of Delaware

Application April 10, 1945, Serial No. 587,571

2 Claims. (Cl. 170—159)

1

My present invention relates to a fan blade structure of simple and light construction.

One object of the invention is to provide a fan blade structure formed of a non-metallic material such as paper base material, or laminated phenolic plastic instead of the usual metal blades whereby the blade can be produced with a minimum of effort and expense and balanced with a minimum of effort.

Another object is to provide a blade which is safer than the usual metal blade due to its lightness and its quality of being more resilient than metal, thereby reducing the possibility of physical harm to anyone happening to come in contact with the blade while it is rotating.

Still another object is to provide a fan blade which can be cut from a sheet of thermo-plastic material and then heated and formed to the desired shape to produce pitch for air delivery, or cut from a semi-cured material which becomes completely cured and takes a set upon the application thereto of pressure and/or heat.

With these and other objects in view, my invention consists in the construction and arrangement and combination of the various parts thereof whereby the objects contemplated are attained as hereinafter more fully set forth, pointed out in my claims and illustrated in the accompanying drawings, in which:

Figure 1 is a side elevation of a fan blade structure embodying my invention;

Figure 2 is a front elevation thereof showing in dotted lines the original flat shape of the fan blades;

Figure 3 is a rear view of the structure;

Figure 4 is an enlarged sectional view on the line 4—4 of Figure 1; and

Figure 5 is a bottom plan view of the hub and center plate of Figure 4 before the fan blades are connected thereto.

On the accompanying drawings I have used the reference numeral 10 to indicate a fan blade. Four of the blades are shown and they are connected together at the center by a disk-like portion 12, the four blades 10 and the portion 12 being all formed of a single sheet of material and in the initially flat shape shown by dotted lines 10a in Figures 1 and 2.

The disk-like portion 12 is reinforced by a metal plate 14 of disk-like character formed on a hub 16. The hub 16 is adapted to be secured to a shaft 18 of an electric motor or the like as by a set screw 20. The plate 14 has a central extension 22 formed with a pair of beads 24 which fit a similarly shaped center hole 26 of the

2

disk-like portion 12 of the fan blades. The disk-like portion is also provided with perforations 28 through which studs 30 of the plate 14 extend, and for assembly purposes these are riveted as at 32 over a metal disk 34. The central portion 12 of the fan blades is thereby confined between the disks 14 and 34 which suitably reinforce the blades and provide a good mechanical connection to a shaft for rotating the fan structure.

It will be noted that adjacent the periphery of the disk 14 corrugations 36 are formed in the material of the fan blades 10 for the purpose of reinforcing the blades at the transition point from the hub plate 14 to the main body of each blade 10.

The method involved in forming the fan structure is as follows: First, the blades 10 and the center disk portion 12 are cut from a single sheet of non-metallic material such as a thermo-plastic or a laminated phenolic plastic to the shape shown by dotted lines in Figures 1 and 2. The blades are then heated in order to make them plastic and while heated they are formed in a press to the proper angle or pitch for air delivery upon rotation, these angles being best shown in Figure 2. The blade structure is then permitted to cool so that the blades set in the shape to which they were formed in the press and retain such shape under ordinary moisture and temperature conditions.

In the case of a blade which is made of semi-cured material the blade becomes completely cured and takes its set when it is finally formed in the press, the curing resulting from the pressure produced by the press. At the same time, heat may be applied in addition to the pressure to completely cure the material.

After the blades are formed as just described they are assembled relative to the hub 16 in the manner already described to form a completed fan blade structure which can be mounted on a shaft of a fan motor or the like.

The resulting structure is light in weight and thus safer to operate. It is inexpensive to manufacture both from the material and labor standpoint. The material is readily cut in a die and formed in a press after the material is heated to make it plastic. The subsequent operations of assembling the hub and the disk 34 are simple to perform, and balancing the structure may be quickly and conveniently done by trimming off the heavy blades until proper balance is secured.

Some changes may be made in the construction and arrangement of the parts of my fan structure and the steps of the method can be

varied without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. In a fan blade structure, a plurality of blades integral with a central disc portion, said blades and disc portion being of non-metallic material, said blades being shaped to provide pitch for air delivery resulting from rotation of the structure, and a metallic hub for said fan blades having a plate-like portion, said central disc portion of said fan blade structure being connected to said plate-like portion, each blade at its innermost portion adjacent said disc portion being arcuate shaped in radial cross-section, and said inner-most portion having reinforcing corrugations extending radially outward from the periphery of said central disc portion.

2. A fan blade structure comprising a sheet of non-metallic material shaped to provide a plurality of blades connected together by a cupped central disk-like portion, a metallic reinforcing disk therefor, said blades being permanently formed to produce pitch for air delivery resulting from rotation of the structure, and a metallic hub for said structure having a plate-like portion provided with studs extending through said disk-like portion and said reinforcing disk and

riveted, each blade adjacent the periphery of said plate-like portion of said hub having reinforcing corrugations in the transition portion of the blade from the periphery of the disk like portion to the main portion of the blade, said corrugations being entirely opposite the cupped side of the plane of said plate-like portion of said hub.

GEORGE L. MOELLER.
